ATTORNEY.

UNITED STATES PATENT OFFICE.

WALTER J. TIDD, OF SPRINGFIELD, MASSACHUSETTS, ASSIGNOR TO TIDD RECORDING CLOCK COMPANY, OF SPRINGFIELD, MASSACHUSETTS, A CORPORATION OF MASSACHUSETTS.

WATCHMAN'S TIME-RECORDER.

1,340,578.

Specification of Letters Patent. Patented May 18, 1920.

Application filed March 21, 1917, Serial No. 156,417. Renewed October 13, 1919. Serial No. 330,521.

To all whom it may concern:

Be it known that I, WALTER J. TIDD, a citizen of the United States of America, residing in the city of Springfield, county of 5 Hampden, and State of Massachusetts, have invented certain new and useful Improvements in Watchmen's Time-Recorders, of which the following is a specification.

This invention relates to improvements 10 in watchmen's time recorders or clocks, and is particularly designed for use by policemen or other watchmen during their regular trips of inspection to record the time he makes his regular trips or beats. The invention, broadly, comprises a clock mechanism 15 which is mounted in a suitable inclosing casing with means for detachably connecting the inclosing case to the inside of a door or other part of the building, preferably, to the inside of the outside door of 20 a store or other place of business. The clock mechanism is provided with means for supporting a dial, which shows numerals and spaces indicating either twelve or twenty- 25 four hours, is carried by the hour post of a clock. Suitable means are provided for perforating this dial by the operator from the outside of the door. A suitable device is also provided for positioning this dial.

30 The invention further comprises means for securing the dial to the hour post, whereby a new dial may be readily applied and the old one removed. A further object of the invention is to provide a plate device for 35 readily attaching the clock case to the door, and means for attaching the clock case to the plate. These and other objects will appear in the body of the specification and will be particularly pointed out in the 40 claims.

Referring to the drawings:

Figure 1 is a vertical sectional view 45 through the axis of the clock inclosing casing illustrating the perforating rod which extends through the door, and the dial which is engaged by the perforating point;

Fig. 2 is a view similar to Fig. 1 but illustrating on an enlarged scale the dial perforating mechanism, also illustrating the 50 clip device for securing the paper dial to the hour post and the plate carried thereby;

Fig. 3 is a front elevational view of the dial showing the flat spring clip which se-

cures the dial to the hour post, the clip being formed with a slot to receive a pin on the 55 hour post, and a cut-out portion at the end thereof for receiving a pin for adjusting the clip on the hour post;

Fig. 4 is a modification of the perforating mechanism in which the perforating pin is 60 operated by a spring on the clock movement instead of on the attaching plate;

Fig. 5 is a view showing the plate that is detachably secured to the inside of a door and to which the clock casing is hinged. 65 This view shows the clock casing in a lowered or open position, and the pin operating spring secured to the plate;

Fig. 6 is a detail view of the detachable hinge connection between the clock casing 70 and its attaching plate.

Referring to the drawings in detail: 1 indicates the door or other part of the building, 2 is an attaching plate that is secured to the inside of the door and to which the 75 clock casing 3 is pivotally attached by means of a hinge which is indicated as a whole at 4. The clock movement, as a whole, is indicated by the numeral 5 and the usual winding key at 6 and hand setting button at 7, 80 which operates the hour post 7' in the usual way. 8 is a metal plate on which the paper disk 9 is placed. This plate is operated by the hour post 7' and, therefore, rotates therewith. This disk is secured in place by means 85 of the spring clip 10, shown in front elevation in Fig. 3 and comprises a strip of spring metal having the slotted portion 11 to receive the pin 12 on the hour post 13. The end of the clip is cut out, as indicated at 14 to receive the pin 15. It will be seen that the graduated paper disk 9 may be removed by simply lifting the cut out end portion of the strip 10 so as to disengage the same from the pin 15 then slightly turning the spring clip 95 10 so that the pin 12 registers with the slot 11, whereby the clip as a whole can be removed. The pin 15 serves the further purpose of correctly positioning disk 9 so that

when the same is placed on the plate 8 the 100 hour divisions will correspond with the correct time. Extending through the door 1 is the slidable rod 16 having an operating head 17. The end of this rod is formed with an enlarged head 18 which engages a spring 19 105 which is attached to the inside of the plate 2,

as clearly shown in Figs. 5 and 6. This spring serves the purpose of holding the rod 16 in a normally extending position. When the operator pushes the rod 16 inward the 5 spring 19 is bent or flexed so as to cause the sharpened point 20 that is carried by the spring 19 to perforate the paper disk 9. The point 20 passes through the retaining clip 21 which clip is for the purpose of preventing 10 the paper from sticking to the sharpened point when the spring 19 and the pin 20 is retracted, two of the perforations being indicated in Fig. 3 at 22. The plate 2 is secured to the door 1 by means of the bayonet 15 connection which comprises enlarged openings 23 and the screw head 24 which passes through this opening and then the shank of the screw enters a smaller portion of the slot 23. The casing 3 is locked to the plate 20 2 by means of the spring clip 25.

Referring to the modification shown in Fig. 4: Instead of having the spring 19, shown in Fig. 5, a compression spring 26 is located on the rod 27 of the clock movement. 25 Also mounted on this rod is an angular shaped plate 28 engaging the head 18 of the pin 16. The sharpened point 20 is carried by the plate 28. It will be seen that when the rod 16 is operated this plate will be 30 moved on the rod 27 against the compression spring 26 and the perforation of the paper disk is effected in the same manner as before described. One of the important features of the present invention is that the operating pin 16 is entirely disconnected from the clock case or clock movement, thus making the recording device very easy to install. Another advantage is that the changing of the disk or dial 9 can be readily accomplished 35 by simply lowering the casing 3, removing the clip 10 and substituting a new paper disk in its place. Fig. 6 illustrates in detail the construction of the hinge connection 4 between the plate 2 and the clock casing 3. 40 Attached to the casing 3 is a pin 26' by means of the clip or bracket 27, the outer end of which is formed with a projection 28', which enters the slot 29 of the complementary hinge part 30. The projection 28' 45 can only enter the slot 29 as the casing 3 and plate 2 are in the same plane. The projection 28' prevents the casing 3 from becoming detached from the plate 2 when the same is opened to the position shown in Fig. 5. 50 It is understood that various modifications embodying the above principles may be made without departing from the spirit and scope of the invention. Another important feature of the present invention is 55 that it does not require any change in construction of the clock mechanism since the paper dial is readily detached to the hour post of the clock.

What I claim is:

60 1. In a watchman's time recorder, the

combination with the inside portion of a door, of a rod slidably mounted therein, and formed with a head on the inner end thereof to retain the same in place and for engaging a spring mounted perforating pin, 70 a clock movement, a recording disk removably secured thereto, a casing for the movement, said casing being pivotally secured to the inside of the door, a spring mounted perforating pin that is secured to the inside of 75 the door and normally held away from the recording disk, said disk being operated by the hour post of the clock and located adjacent to and slightly spaced away from the inner side of the door, and a spring clip 80 having a slot and pin connection with the hour post for holding the graduated disk in place, means comprising a plate secured to the inner side of the door for detachably removing the clock mechanism as a whole 85 and to which the spring mounted perforating pin is secured.

2. In a watchman's time recorder the combination with a clock movement, an inclosing casing therefor, a recording disk, a 90 plate having opening therethrough to receive attaching devices that are secured to the inside of the door and to which the clock casing is pivotally connected, said plate having a spring fixedly secured thereto and located on the inner side of the plate that is secured to the door, a disk perforating point carried by the spring, and movable only toward and away from the disk in the same plane, an operating rod 100 permanently secured to the door and designed to engage the spring and actuate the perforating point, said push rod being normally held in an outward position by said spring when not in use, as described. 105

3. In a watchman's time recorder the combination with the inside surface of a door, of a clock movement, means comprising a plate which is detachably secured to the door and to which the movement is pivotally connected to permit the same to be lowered, a spring carrying a perforating point and fixedly secured to the inside surface of the plate, a push rod passing through the door and normally engaging the spring, 110 and having a head to retain the same in place in the door, said perforating point being located in a space between the inside of the door and the recording disk on the clock movement, whereby when the push-rod is 115 operated the pin will move across the free unobstructed space between the plate and disk, as described.

4. A watchman's time recorder comprising in combination, a one-piece inclosing 125 casing for the clock movement, means for securing the casing to the inner side of a door comprising a plate that is detachably secured to the door, and to which the casing is pivotally secured, a recording disk 130

carried by movement and spaced away from the plate, and having the same divided into hourly spaces, a perforating pin for engaging the disk, and secured to the plate by means of a flat spring to permit its free end to move only toward and away from the plane of the disk, a push rod permanently secured to and extending through the door and engaging the flat spring to move the same and its perforating part against the disk, said spring serving to normally retain the push rod retracted.

WALTER J. TIDD.
